UNITED STATES PATENT OFFICE

94,482

DESIGN FOR A BUREAU OR SIMILAR ARTICLE

Clayton M. Hawk, Grand Rapids, Mich.

Application December 17, 1934, Serial No. 54,451

Term of patent 3½ years

To all whom it may concern:

Be it known that I, Clayton M. Hawk, a citizen of the United States, residing at Grand Rapids, Kent County, State of Michigan, have invented a new, original, and ornamental Design for a Bureau or Similar Article, of which the following is a specification, reference being had to the accompanying drawing, forming a part thereof.

The figure is a perspective of the bureau or similar article showing my new design.

I claim:

The ornamental design for a bureau or similar article, as shown.

CLAYTON M. HAWK.
